UNITED STATES PATENT OFFICE.

ROBERT A. BAYLES, OF STOCKTON, CALIFORNIA.

EXCAVATING-MACHINE.

1,335,932.

Specification of Letters Patent.

Patented Apr. 6, 1920.

Application filed March 25, 1919. Serial No. 285,040.

To all whom it may concern:

Be it known that I, ROBERT A. BAYLES, a citizen of the United States of America, residing at Stockton, in the county of San Joaquin, State of California, have invented 5 certain new and useful Improvements in Excavating-Machines; and I do declare the following to be a clear, full, and exact description of the same, reference being had 10 to the accompanying drawings, and to the characters of reference marked thereon, which form a part of this application.

This invention relates to improvements 15 in excavating machines, and particularly to a type adapted to excavate and dig ditches and the like; the principal object of the invention being to produce a machine which can be used to dig a ditch of any depth or width, and which will deposit the dirt so 20 excavated off to one side of the ditch, leaving a furrow or ditch clean of loose earth.

A further object has been to produce a 25 machine which will be simple of operation and yet extremely efficient for the purpose for which it is designed.

These objects, I accomplish by means of such structure and relative arrangement of the parts as will fully appear by a perusal of the following specification and claims.

30 On the drawings, similar characters of reference indicate corresponding parts in the several views.

Figure 1 is a side elevation of my improved excavator with the earth on one 35 side of the ditch being dug cut away.

Fig. 2 is a similar view, taken on the opposite side of the machine.

Fig. 3 is a cross sectional view, taken relatively on a line 3-3 of Fig. 1.

40 Fig. 4 is a fragmentary view of a plow adjustment means taken on a line 4-4 of Fig. 1.

Referring now more particularly to the numerals of reference on the drawings, the 45 numeral 1 represents a pair of spaced and suitably connected longitudinal frames, between which is journaled a large wide face wheel 2 having spokes 3 on one side of the same. From this side a frusto-conical ring 50 4 extends inwardly, forming a V-shaped pocket 5 all around the inner periphery of the wheel 2 adjacent the side having the spokes 3 thereon. This pocket is subdivided by a plurality of vanes or plates 6 suitably 55 spaced around the wheel and extending from

the side of the wheel opposite to the spokes to the ring 4 and being connected thereto.

Positioned on the latter side of the wheel and flexibly mounted to the frame 1 is a plow beam 7 having a plow share 8 secured 60 to the same in such a manner that the dirt turned up thereby will be deposited in the pockets 5 of the wheel 2.

The pulling strain on the plow beam is taken by a chain 9 secured thereto at the 65 forward end and to a swing or double tree 10 mounted for vertical adjustment relative to the frame 1 by means of a slotted bar 11, which member 10 is adapted to be hitched up with draft animals to pull the 70 excavator.

The angle of the plow relative to the frame, or the depth at which the plowing is to be done relative to the wheel 2 is regulated at the forward end by means of a chain 75 12, adapted to be wound on a shaft 13 by some such means as a worm drive 14 operated by a hand wheel 15 from the driver's seat 16 at the rear of the excavator. The rear end of the plow is held in adjustable 80 position by means of a rectangular bar member 17 pivotally mounted thereto, one side of which is slotted as at 18 and adjustably secured to the frame through such slot.

Positioned in the wheel 2 above the center thereof is a hopper 19 rigidly mounted to the frame 1, which hopper is adapted to discharge onto a short endless conveyer belt 20, whose outer end is adjustable for height at its forward end as shown at 21. This conveyer discharges onto a conveyer 22, of a length sufficient to discharge its contents a considerable distance from the machine, the outer end being adjustable as to height and being so adjusted and held by means of a 90 chain 23 adapted to be let out or drawn up by means of a hand wheel mechanism 24 near the seat 16.

Both conveyers are chain driven, such driving means being transmitted through 100 bevel gears 25, which are driven with the rotation of the wheel 2 by means of a chain 26 on a sprocket 27 on the wheel 2. The upwardly riding side of the wheel 2 above the center thereof and to the hopper 19 has a curved plate 28 following the inner periphery of the ring 4 and extending across the face of the wheel in order that the dirt in the pockets will be retained therein until the hopper 19 is reached.

The rear end of the excavator is supported by a wheel 29 adjustable for height by any suitable means such as the ratchet-held lever 30.

5 Side balance for the machine is had by means of a wheel 31, set on an offset shaft 32 adapted to be clamped in any desired position in the bearing 33, which is adapted to be clamped at any desired point to a beam 10 34 extending at right angles from the frame 1 on the side opposite to the conveyer and plow mechanisms. This wheel is adapted to rest on the bank of the ditch which is being dug to balance the machine, but the 15 offset portion of the shaft 32 is of sufficient length to enable the wheel 31 to ride on the ground at the same level as the wheel 2 when the machine is being moved over even ground. In the operation of the machine, 20 the plow is first lowered a certain distance below the level of the wheel 2 by means of the forward and rear adjustments in order to make the initial cuts in the ground. The wheel 2 then rides in these cuts, and 25 the plow is operated to cut a furrow alongside to the desired depth, the operation being repeated back and forth until the desired width and depth of ditch has been attained. The dirt from the plow is emptied into the 30 pockets 5 in the wheel, and this dirt is then discharged into the hopper 19 and deposited to one side of the machine by the conveyer 22.

Thus, from the foregoing description it 35 will readily be seen that I have produced such a device as substantially fulfills the objects of the invention as set forth herein.

While this specification sets forth in detail the present and preferred construction

of the device, still in practice, such deviations from such detail may be resorted to as do not form a departure from the spirit of the invention, as defined by the appended claims.

Having thus described my invention, what I claim as new and useful and desire to secure by Letters Patent is:—

1. An excavator comprising a frame, a wide faced wheel mounted therein, a plow positioned adjacent one side of the wheel, 50 a balance wheel on the opposite side of the first named wheel, and means whereby the balance wheel may be adjusted both for height and transverse distance relative to the first named wheel.

2. In an excavator having a frame, a wide faced wheel mounted therein and a balance wheel on one side thereof, means whereby the balance wheel may be adjusted both for height and transverse distance relative to the 60 first named wheel, such means including a beam projecting from the frame at right angles thereto, a carriage adjustably mounted to the beam for longitudinal movement relative thereto, and a shaft extending parallel 65 to the beam and adjustably clamped to the carriage against turning movement relative thereto, the shaft having an extension thereon beyond the carriage at right angles to the beam, the balance wheel being mounted 70 on this extension and parallel thereto.

In testimony whereof I affix my signature in presence of two witnesses.

ROBERT A. BAYLES.
